US00D867337S

(12) **United States Design Patent** (10) Patent No.: **US D867,337 S**
Kitamura et al. (45) Date of Patent: **** Nov. 19, 2019**

(54) **REMOTE CONTROLLER FOR ELECTRICAL
HOUSEHOLD APPLIANCE**

(71) Applicant: **MITSUBISHI ELECTRIC
CORPORATION**, Tokyo (JP)

(72) Inventors: **Kenshiro Kitamura**, Tokyo (JP);
Daisuke Iizawa, Tokyo (JP); **Ryo
Yoshida**, Tokyo (JP); **Kensho Motoe**,
Tokyo (JP)

(73) Assignee: **Mitsubishi Electric Corporation**,
Tokyo (JP)

(**) Term: **15 Years**

(21) Appl. No.: **29/622,105**

(22) Filed: **Oct. 13, 2017**

(30) **Foreign Application Priority Data**

Apr. 17, 2017 (JP) 2017-008143

(51) LOC (12) Cl. **14-03**

(52) U.S. Cl.

USPC **D14/218**; D13/168

(57) **CLAIM**

The ornamental design for a remote controller for electrical household appliance, as shown and described.

DESCRIPTION

FIG. 1 is a perspective view of the front, right, and top sides of a remote controller for electrical household appliance showing our new design;

FIG. 2 is a front view thereof; a rear view being a mirror image thereof;

FIG. 3 is a right side view thereof; a left side view being a mirror image thereof;

FIG. 4 is a top plan view thereof; a bottom plan view being a mirror image thereof;

FIG. 5 is a reference perspective view showing a first energized state thereof;

FIG. 6 is a reference perspective view showing a second energized state thereof;

FIG. 7 is a reference perspective view showing a third energized state thereof;

FIG. 8 is a reference perspective view showing a fourth energized state thereof;

FIG. 9 is a reference perspective view showing a fifth energized state thereof; and,

FIG. 10 is a reference perspective view showing a sixth energized state thereof.

1 Claim, 10 Drawing Sheets
